SAWMILL FEED WORKS CONTROL AND
REVERSING MECHANISM

Andrew G. Petersen, Showlow, Ariz.

Application December 12, 1950, Serial No. 200,466

3 Claims. (Cl. 143—106)

1

This invention pertains to saw mill feed works control and reversing mechanism.

Heretofore small saw mills not using steam power have been operated by various types of friction drives. Power is usually furnished by internal combustion engines or by electric motors. It has been found that it is inefficient to attempt to compress air and operate the log carriage by pneumatic means similar to steam operation, therefore some means of mechanical operation of the carriage is necessary. Frictional control mechanism, as heretofore used, has been characterized by the use of belts, friction drums, and/or combinations of the two. All these have a common fault in that there is excessive wear on the belts and frictional surfaces and a great deal of manual power is required to shift and/or tighten the belts, or other mechanisms, necessary to obtain the forward and backward motion of the saw log carriage.

In view of the foregoing, one of the objects of my device is to provide mechanism for positive control of power to the saw mill carriage in a manner so that manual control is easy and accurate, thus enabling the sawyer to move the carriage in either direction and at any speed and stop it at any point in its travel, instantly.

Another object is to provide a control mechanism which has a minimum amount of drag and loss of power resulting therefrom.

Another object is to provide a control for the purposes above stated wherein clutches are used to transmit rotation from the driving to the driven parts which have their surfaces enclosed and protected and constructed in such a manner and of such materials that wear and replacement of parts is held to a minimum.

Still another object is to provide a mechanism in which the use of leather or rubber belts is completely eliminated and power is transmitted from various shafts by means of clutches and chains, or the equivalent.

Other objects will appear hereafter.

I attain the foregoing objects by means of the devices, constructions, and combinations of parts illustrated in the accompanying drawings in which—

Figure 1 is a plan view of the log carriage drive;

Figure 2 is a sectional elevation of the main shaft and clutches carried thereon;

Figure 3 is a side elevation of the carriage drive as viewed from the left side of Figure 1;

Figure 4 is a side elevation of the device as viewed from the right side of Figure 1; and

2

Figure 5, Sheet 1, is an elevational view of the inner face of one of the clutches, taken on line 5—5, Figure 2.

Similar numerals refer to similar parts in the several views.

In the drawings, 2 indicates a rectangular horizontally disposed frame made of timbers, or the like, in which the shafts hereafter described are transversely journaled; 3 indicates the saw mandrel or driving shaft located in the outer end portion 9 of the frame; 4 indicates the main, or clutch shaft centrally positioned in the frame; and 5, the jack shaft which is positioned beneath the frame and toward the inner end 10 of frame 2; and 6 the cable drum shaft which is disposed near the inner end 10 of the frame.

In the form of the device here illustrated, power is taken from the saw mandrel or drive shaft 3 and transmitted to clutch drums 7 and 8 which are positioned near the ends of clutch shaft 4, by means of chains. Chain 11 runs from sprocket 12 on shaft 3 over a sprocket 14 attached to clutch drum 8 journaled on the left end portion of shaft 4 as viewed in Figure 2, then over a sprocket 15 on jack shaft 3, and finally over an idler sprocket 17 on idler frame 18, and thence back to sprocket 12. The outside of the lower lay 19 of chain 11 engages the teeth of sprocket 14 on drum 8. The outer bend of the chain runs over sprocket 15 on jack shaft 5 and the upper lay 21 of chain 11 runs over idler sprocket 17 which serves to raise chain lay 21 over sprocket 14 and to tighten the chain, as desired. Since drum sprocket 14 is driven by the outside of chain 11 it rotates in a direction opposite to that of shaft 3. Shaft 3 rotates in the direction indicated by arrows 3a so that the load drag is directly applied from sprocket 12 to drum sprocket 14. Since, however, sprocket 15 on jack shaft 5 is at the end of chain 11 it is driven and rotates in the same direction as shaft 3. A sprocket 20 on the right end of jack shaft 5 then drives a sprocket 23 on clutch drum 7, which is journaled on the right end portion of the clutch shaft 4 by means of chain 24. Since this chain runs directly from the sprocket 23 on the jack shaft 6 to the sprocket of the second or right hand clutch drum 7, this drum will turn in the opposite direction to clutch drum 8.

Clutch shaft 4 is also provided with a driving sprocket 26, which carries chain 27 to driven sprocket 28 to transmit motion to shaft 6, which carries a cable drum (not shown) around which cables are wound to operate the log carriage toward and from the saw in the usual manner.

Both clutch drums are cup shaped and are journaled on the end portions of shaft 4 by bearings 31 so that they normally turn freely. The open end of each drum faces inwardly toward the center of the main shaft 4. Adjacent the open end of each drum there is a clutch shoe supporting hub 32 keyed to shaft 4. Clutch shoes 35 are supported on hubs 32 and revolve with shaft 4. These shoes are of the internally expanding type and frictionally engage the inner annular surface 34 of their respective drums when expanded by hydraulically operated pistons within cylinders 33. The supporting hubs 32 also carry master or pump cylinders 36 which have pistons with piston rods 37 extending parallel to the axis of shaft 4 and eccentrically disposed relative thereto. The master cylinder of each hub is connected by tubing 38 to clutch shoe expanding cylinder 33 of the clutch shoes of this hub. The piston rod 37 of each master cylinder extends toward the central portion of the main shaft 4 and is provided with a contact pad 40. Each brake shoe hydraulic operating mechanism is substantially the same, although they are disposed on the respective right and left end portions of shaft 4 and in reversed positions.

In the center of main shaft 4 there is a spool shaped operating thimble 44, which is slidably keyed thereon. This thimble has flanges 42 at each end, the outer faces of which are adapted to contact the pads 40 on the adjacent ends of the master cylinder piston rods. Between these flanges is an annular groove 48, the inner opposite faces of which are adapted to contact rollers 50 on the control yoke 52. This control yoke is supported on control shaft 56 to the outer end of which the sawyer's control lever 58 is attached.

Movement of the upper end of the sawyer's control lever 58 forces the operating thimble either to the right or left, as desired. When the thimble is moved in either direction from the neutral center position the outer face of the flange on the side in the direction moved contacts the master piston rod pad 40 on this same side. This forces hydraulic fluid from this master cylinder 33 to the clutch shoe cylinder 33 of the clutch on the same side, and expands the clutch shoes so that they engage the clutch drum within which they operate. The main shaft 4 is then forced to turn in the direction in which this drum is rotating. Shifting of thimble 44 in the opposite direction releases the drum above mentioned and causes the other clutch shoe of the opposite drum to expand and engage the opposite clutch drum which is rotating in the opposite direction. Since the clutch shoe supporting blocks are each connected to the main shaft, the main shaft will be driven in the direction imparted by the drum which is clutched. When the thimble 44 is centrally positioned, it does not contact either pump cylinder piston rod pad and no driving motion is imparted to the main shaft. It may then be said to be in neutral position.

In use, the driving shaft may be the saw mandrel shaft. Shaft 6 is connected to the log carriage cable drum, as above stated. Motion of the handle 69 of the sawyer's lever 58 will slide thimble 44 to the left, as viewed in Figure 2. This will contact the left flange of the thimble with pad 40 of pump cylinder piston rod 37 on this same side. The pump cylinder will deliver oil pressure to clutch shoe cylinder 33 within clutch drum 8 and the clutch shoes 35 within this drum will expand and engage this drum

which is rotated counterclockwise as viewed from Figure 3. Shaft 4 will be rotated accordingly and this motion will be imparted to shaft 6 on which the cable drum is mounted.

If the handle of the sawyer's lever 58 is drawn past center in the other direction, clutch drum 8 is released, clutch drum 7 engaged and shafts 4 and 6 will be rotated in the other direction. When lever 58 is vertically positioned so that rollers 50 do not push thimble 44 either to the left or right the feed works is neutral and no rotation is applied to shaft 6.

While I have disclosed but one example of my feed works it will be obvious to those familiar with the art that many modifications of the combined arts are possible and many different adaptations of the device may be made. Therefore, I wish to be limited only by the claims.

I claim:

1. In a sawmill feed works and log carriage control mechanism having a horizontally disposed rectangular frame, a driving shaft transversely journaled thereon, a log carriage drum shaft transversely journaled thereon, a clutch shaft transversely journaled thereon, between said driving shaft and said log carriage drum shaft, driving said log carriage drum shaft by chain and sprocket means, mechanism for driving said log carriage drum shaft in either direction consisting of hydraulically operated clutches positioned on the end portions of said clutch shaft having clutch drums journaled on said shaft and driven by chains and sprockets from said driving shaft in opposite directions, clutch shoes to engage and operate said drums, supported on hubs keyed to said clutch shaft, and hydraulic clutch shoe operating cylinders having piston rods extending parallel to, and toward the central portion, of said shaft, said cylinders being attached to said hubs; a control thimble slidably keyed to the central portion of said clutch shaft having an annular groove and end flanges adapted to engage said piston rods when said thimble is slid from normal central position on said shaft toward either of said piston rods, a control shaft longitudinally journaled in the center of said frame having a sawyer's control lever extending upward from one of its ends and a control yoke extending downward from its other end and engaging in the annular groove of said control thimble to communicate sliding motion to said thimble when said control lever is moved from side to side.
2. In a sawmill feed works for controlling the direction and speed of a cable drum shaft, having a horizontally disposed frame, a transverse driving shaft journaled on one end thereof, a cable drum shaft transversely journaled on the opposite end portion of said frame, and a clutch shaft transversely journaled in the mid portion thereof; mechanism for transmitting rotary motion from said drive shaft to said cable drum shaft in either direction, consisting of cup shaped clutch drums with inner annular friction surfaces opening toward the central portion of said clutch shaft journaled on the end portions of said shaft, hubs keyed to said shaft adjacent the open ends of said drums supporting internally expanding clutch shoes operated by pistons in hydraulic cylinders supported on said hubs, hydraulic pump cylinders connected to said clutch shoe cylinders and also supported on said hubs and having pistons with piston rods extending toward the central portion of said clutch shaft,

parallel to the axis thereof and directed toward the central portion thereof, a control thimble centrally positioned and slidably keyed on said clutch shaft having end flanges adapted to engage the ends of the piston rods of said pump cylinders when moved axially from the central portion of said shaft and also having a centrally positioned annular groove; a control shaft journaled longitudinally on said frame having an outer end extending beyond the end of said frame, an inner end positioned over the central portion of said clutch shaft; a sawyer's control lever attached to and extending radially upward from the outer end of said control shaft, a yoke attached to the inner end of said control shaft, extending downward and engaged in the annular groove of said control thimble; chains and sprockets operating between said driving shaft and said clutch drums to rotate said drums in opposite directions; a chain and sprocket mechanism extending from said clutch shaft to said cable drum shaft to drive said cable drum shaft in the same direction as that of said clutch shaft when motion is imparted thereto by the engagement of the clutch shoes thereon with said clutch drums.

3. In a sawmill feed works and log carriage control mechanism having a horizontally disposed rectangular frame, a driving shaft transversely journaled thereon, a log carriage drum shaft transversely journaled thereon, a clutch shaft transversely journaled thereon, between said driving shaft and said log carriage drum shaft, driving said log carriage drum shaft by chain and sprocket means, hydraulically operated clutches positioned on the end portions of said clutch shaft having clutch drums journaled on said shaft and driven by chains and sprockets from said driving shaft in opposite directions, clutch shoes to engage and operate said drums, 25

5 supported on hubs keyed to said clutch shaft, and hydraulic clutch shoe operating cylinders having piston rods extending parallel to, and toward the central portion of, said shaft, said 10 cylinders being attached to said hubs; mechanism for controlling the operation of said clutch from a sawyer's control lever at one end of said frame so as to vary the direction of said log carriage drum shaft, consisting of a control thimble slidably keyed to the central portion of said clutch shaft having an annular groove and end flanges adapted to engage the piston rods of said 15 hydraulic clutch shoe operating cylinders when said thimble is slid from normal central position on said shaft toward either of said piston rods, a control shaft longitudinally journaled in the center of said frame having an outer end extending beyond one end of said frame, a sawyer's control lever extending upward from said outer end and a control yoke extending downward from its opposite end and engaging in the annular groove of said control thimble to communicate sliding motion to said thimble when said control lever is moved from side to side.
